UNITED STATES PATENT OFFICE.

RAFFAELLO LA PEGNA, OF MILAN, ITALY.

TYPEWRITER.

Original application filed December 5, 1921, Serial No. 520,119. Divided and this application filed May 22, 1923. Serial No. 640,761.

To all whom it may concern:

Be it known that I, RAFFAELLO LA PEGNA, subject of the King of Italy, residing at Milan, Italy, have invented certain new and useful Improvements in Typewriters, of which the following is a specification.

The present invention relates to typewriters and has for its object a typewriter in which each desired type may be printed 10 at the same time in a number of separate printing points by the manipulation of a single key.

The typewriter according to this invention is particularly useful in connection 15 with bookkeeping, in which it is often necessary to write a given numeral, figure or word in two or more columns or rows of a page.

The typewriter according to this invention comprises a frame, a carriage travelling on said frame and carrying a book or a sheet of paper to be written thereon, a number of type sets said sets being spaced from each other and comprising a number of 25 printing mechanism each of which actuates a type for its printing, means for coupling together in operation any desired number of said sets and means for operating the coupled sets to obtain the impression of any 30 desired type in all said selected sets at the same time by the manipulation of a single operating key.

On the annexed drawings is shown by way of example an embodiment of a multiple typewriter according to this invention; and in the figures the typewriter is assumed to be intended to write numerals or figures, but of course any desired characters or signs may be used in the keyboard.

In said drawings: Figure 1 is the plan view of a typewriter according to this invention in which the several printing mechanisms are provided with mechanical controlling parts; Figure 2 is a section to 45 an enlarged scale on the line 2—2 of Figure 1; Figure 3 is the plan view to an enlarged scale of a separate printing set; Figure 4 is a perspective view of a device for connecting in operation the several desired type sets; Figure 5 is a perspective view of the 50 end portion of the carriage showing the member intended to release the several printing mechanisms after the carriage has completed a line of writing.

In the construction shown by figures 1, 2 and 3, 1 is a frame or support on which are

mounted a number of type sets, each set being designated as a whole by a reference I, II, III, IV, V; and it is assumed that the apparatus comprises five sets but of course 60 the number of these sets may be any desired one; said sets being hereinafter particularly described and the several mechanisms of each set are adapted to strike the respective types at a common printing point 65 shown on the drawing by the reference 2.

Said type sets, which may be in any desired number, as above stated, are located at a desired distance from each other, each of them being in position to write on a desired 70 point of the printing surface which may be a paper sheet, a book page or the like. At one side of the apparatus may be located a typewriter of any conventional or preferred construction which is designated as a whole 75 by the reference 3; and each of the said type sets may comprise a larger number of keys and types than that shown on the drawing and one of them may be a typewriter adapted to write any other desired character. 80

At the front of the apparatus is movably mounted a carriage 5 having rollers 4' running on rails 4 and a rack bar 6 cooperating with the usual trip pawl 7 which controls the progression of the carriage after each 85 actuation of a key. A support 8 for the book or paper sheet to be written on is mounted to move vertically in the carriage 5 and in said support is provided a platen 9 acted on by springs 9' for keeping the 90 printing surface in the required position. Said support 8 is provided with rack bars 10 each meshing with a ratchet pinion 11 rigid with a shaft 12. A ratchet wheel 13 is fastened on this shaft and is engaged by 95 a pawl 14 pivoted on an arm 14' which is rotatable around the shaft 12 and is pivotally connected with a hand bar 15 mounted to reciprocate in a support 15' and by means of this hand bar the pawl 14 is operated and the wheel 13 is rotated through one tooth, the support 8 being thus moved vertically through the space of one line. 100

One of said type sets, the one marked by I in the construction illustrated, is provided with ten keys 16' having the digits from 0 to 9. Each key is carried by a lever 16 rigid with a quadrant 17 which is connected by a tie 18 to a rod 19 and this rod is mounted to reciprocate in the support 19' of the 110 machine frame, and is held by a spring 20 in the position illustrated in Figure 2.

Each of said quadrants 17 is rigid with a shaft 37 and said ties 18 run over suitable grooved guide rollers 18'.

Each rod 19 is provided at one end with 5 a tooth 21 adapted to engage a hook 22 pivoted at one end of a reciprocating rod 23. This rod is pin-and-slot connected with one end of a lever 24 which is fulcrumed on a support 25 and has its opposite end pin-and-slot connected with a type bar 26. All the hooks 22 of a printing type set are connected each by a rod 22' with a transverse bar 27 which is connected by a rod 28' with a lever 28 provided with a manipulating key 29. Said bar 27 is carried by two braces 27' fulcrumed at 27" in the machine frame.

The lever 28 is fulcrumed at 30 and is provided with an arm 31 which is pin-and-slot connected with a link 32 pivoted to a 20 lever 33 fulcrumed at 34; the opposite end of said lever being held in engagement with a pawl 36 by a spring 35.

Each key bar 16 is fixed to corresponding shaft 37 extending throughout the length of 25 the typewriter (figure 1) and journaled in bearings provided in the machine frame and not appearing in the drawing; and as hereinbefore described each of said shafts 37 is provided with a quadrant 17 for the operation of the printing mechanism 18—19—23—24—26.

Each of the other sets is similar in construction to the set hereinbefore described with the only difference that they are not 35 provided with keys and therefore they do not require further description.

The sets I, II, III, IV (or at least some of them) are provided with vertical guides 38 in which are slidably mounted yokes each 40 consisting of a transverse cross bar 39, having a key 41, and of vertical bars 40 and each of these bars 40 is in register with the rear end of one of the levers 33.

Said yokes are intended to control the 45 levers 33 so as to put in operative condition the respective printing mechanism sets.

This operation is easily understood by inspecting the figures 1 and 3, in which are shown the bars 33 of the sets II, III, IV, V, 50 the respective numerals of the sets being affixed to the references of these parts. In the embodiment illustrated it is assumed that the set I having the type operating keys is not provided with the bar 33 and associate yokes, but of course this arrangement could 55 also be provided in the set 1.

By inspecting the said figures it appears that by depressing one of the yokes as 39^b—40^b by means of its key 41^b the levers 60 33^{III} and 33^{IV} are depressed against the action of their respective springs 35 and are then held in this position by the pawl 36 which is caused to engage them by the spring 36' and therefore in the sets III and IV the printing 65 mechanism 31—28—28'—27—22'—22—20 is

in the condition of figure 2 and then the actuation of the keys 16, shafts 37, quadrants 17, ties 18 and bars 19 with teeth 21 causes the operation of the type bars 26. On the contrary in the other sets the levers 70 33 are held by their spring 35 in such a position as hold the hooks 22 removed from teeth 21 through the gear hereinbefore described.

As is obvious, by depressing any or all 75 of keys 41^a, 41^b, 41^c and 41^d the pair of sets controlled thereby are put in operative condition; and further any of the sets may be separately put out of operation by lifting the respective key 29. It is to be noticed 80 that the number of yokes 39—40—41 may be any desired one for the purpose of grouping at will the operation of the several type sets notwithstanding that in figure 1 the yokes are shown in numbers of four for the 85 sake of clearness.

In figure 2 no set apex has been affixed to the parts 39, 40, 41, as they would be of no use in said figure.

In front of each of the sets I, II, III, IV, 90 the carriage 5 is provided with a tooth 42 (figures 2 and 5) which is pivoted in such a manner as to rock freely towards the left against the action of its spring 43 while its rocking towards the right is prevented by a 95 stop 44. Said tooth 42 has a slope on its left face, and in the position it takes after the line of writing is completed it engages the end pin 45' of a rod 45 whose other end is connected with the tail of the pawl 36. This arrangement is intended to restore 100 to normal conditions the several levers 33 after completing each stroke of the carriage.

After having put the selected sets in operative conditions, in the manner hereinbefore described, the operator successively manipulates the desired keys 16' and the respective types are struck by the desired gear in the desired sets, the writing being thus 105 typed at the same time in the selected columns of the sheet.

When the carriage 5 reaches the end of its stroke, that is the right end of the written line, the pins 45' of the rods 45 are moved by the teeth 42 of the carriage against the 110 action of the springs 36' and the pawls 36 are caused to release the levers 33.

The several type sets are thus carried into inoperative conditions each time the carriage has reached the end of the written line, and thus the following line may be written in any desired manner after having shifted the platen 8 one space by means of the hand bar 15.

It is understood that the carriage 5 is controlled by a usual spring drum as 5' which cooperates with the trip gears 7 to move the carriage one step at each action of a key; these devices not being particularly shown and described as they are well known 125 130

and may be of any approved or conventional type.

The rods 26 of each printing mechanism converge towards one and the same printing

5 point and the paper carrying carriage is moved one step with regard to said point at each key operation and the desired numerals are thus typed in succession at the side of each other in the several columns 10 corresponding to the type sets put in operation in the machine.

Of course each or a number of the type sets may comprise any number of type bars other than ten, and some of the bars 26 may 15 be provided with other types than that of numerals and the machine may thus be used for writing at the same time the same word or sentence on two or more points of the sheet.

20 The several type sets are of course located at a suitable distance from each other and each or a number of them may consist of a usual typewriter.

It is to be understood that the described 25 machine may be provided with any desired or conventional accessory device as a tabulator, carriage return key and the like. It may also be associated or combined with a computing machine or with any apparatus 30 adapted to effect and record the results of additions and other computing operations.

By the described machine there may be produced at the same time and in a simple and easy manner writings of any kind on 35 several columns or rows of a sheet or of a page of a book and this machine is particularly useful in bookkeeping as it minimizes labor and errors.

What I claim as my invention and desire 40 to secure by United States Letters Patent is:—

1. A typewriter comprising, a frame, a platen carriage mounted to move on said frame, means for producing a step-by-step motion of said carriage, a plurality of type sets each comprising a series of type bars adapted to strike on the same printing point of said platen, said sets being spaced from each other to write on points of said platen 45 at the sides of each other, a master key board for actuating all of said type sets, and releasable connecting means between each key mechanism in said keyboard and the corresponding type bar in each type set.

55 2. A typewriter comprising, a frame, a platen carriage mounted to move on said frame, means for producing a step-by-step motion of said carriage, a plurality of type sets each comprising a series of type bars adapted to strike on the same printing point 60 of said platen, said sets being spaced from each other to write on points of said platen at the sides of each other, a master key board for actuating all of said type sets, releasable connecting means between each key

mechanism in said keyboard and the corresponding type bar in each type set and means for controlling said connecting means for each type set.

3. A typewriter comprising, a frame, a platen carriage mounted to move on said frame, means for producing a step-by-step motion of said carriage, a plurality of type sets each comprising a series of type bars adapted to strike on the same printing point of said platen, said sets being spaced from each other to write on points of said platen at the sides of each other, a master key board for actuating all of said type sets, releasable connecting means between each key mechanism in said keyboard and the corresponding type bar in each type set, controlling means for bringing into operative condition said connecting means for each type set, and means for releasing said connecting means when said platen carriage has completed one stroke.

4. A typewriter comprising, a frame, a platen carriage mounted to move on said frame, means for producing a step-by-step motion of said carriage, a plurality of type sets each comprising a series of type bars adapted to strike on the same printing point of said platen, said sets being spaced from each other to write on points of said platen at the sides of each other, a master keyboard for actuating all of said type sets, releasable connecting means between each key mechanism in said keyboard and the corresponding type bar in each type set, controlling means for bringing into operative condition said connecting means for a number of type sets, and means for releasing said connecting means when said platen carriage has completed one stroke.

5. A typewriter comprising, a frame, a platen carriage mounted to move on said frame, means for producing a step-by-step motion of said carriage, a plurality of type sets each comprising a series of type bars adapted to strike on the same printing point of said platen, said sets being spaced from each other to write on points of said platen at the sides of each other, a master keyboard for actuating all of said type sets, a releasable connecting means between each key mechanism in said keyboard and the corresponding type bar in each type set, controlling means for bringing into operative condition said connecting means for a number of said type sets, means for locking said controlling means in the operative position of said connecting means, and means for releasing said locking means when said platen carriage has completed one stroke.

6. A typewriter comprising, a frame, a platen carriage mounted to move on said frame, means for producing a step-by-step motion of said carriage, a plurality of type sets each comprising a series of type bars

- 4
- adapted to strike on the same printing point of said platen, said sets being spaced from each other to write on points of said platen at the sides of each other, a master keyboard 5 for actuating all of said type sets and releasable connecting means between each key mechanism in said keyboard and the corresponding type bar in each type set, said carriage comprising a support for the surface 10 to be written on, means for holding said surface in the printing plane of said types, and means for the line-shifting of said surface.
7. A typewriter, comprising, a frame, a platen carriage mounted to move on said frame, means for producing a step-by-step motion of said carriage, a plurality of type sets each comprising a series of type bars adapted to strike on the same printing point of said platen, said sets being spaced from each other to write on points of said platen at the sides of each other, a master keyboard 15 for actuating all of said type sets and releasable connecting means between each key mechanism in said key board and the corresponding type bar in each type set, said carriage comprising a support for the surface to be written on, means for holding said surface in the printing plane of said types, rack-bars on said support, pinions 20 meshing with said rack bars and pivoted in said carriage, and means for rotating said pinions for the line shifting of said support.
8. A typewriter comprising a frame, a platen carriage mounted to move on said frame, means for producing a step-by-step motion of said carriage, a plurality of sets of type-bars, each set comprising a series of types adapted to strike on the same printing 25 point and the several sets being spaced from each other to write on separate points of the platen, means in each set for actuating said type bars, means for shifting said actuating means, parts interconnecting the shifting means of the like types in the several sets, 30 means for selectively operating said shifting means, controlling means for putting into and out of cooperation said actuating and shifting means of said several sets, and means 35 operated by hand in each set for shifting said controlling means.

9. A typewriter comprising a frame, a platen carriage mounted to move on said frame, means for producing a step-by-step motion of said carriage, a plurality of sets of type-bars, each set comprising a series of types adapted to strike on the same printing point and the several sets being spaced from each other to write on separate points of the platen, means in each set for actuating said type bars, means for shifting said actuating means, parts interconnecting the shifting means of the like types in the several sets, 55 means for selectively operating said shifting means, controlling means for putting into and out of cooperation said actuating and shifting means of said several sets, said controlling means for each set comprising a lever, a spring forcing this lever towards one of its end positions, means for locking 60 said lever in its opposite position and selectively operating means for moving the said levers of a number of said sets and for engaging them with said locking means.

10. A typewriter comprising a frame, a platen carriage mounted to move on said frame, means for producing a step-by-step motion of said carriage, a plurality of sets of type bars, each set comprising a series of types adapted to strike on the same printing 65 point and the several sets being spaced from each other to write on separate points of the platen, means in each set for actuating said type bars, means for shifting said actuating means, parts interconnecting the shifting 70 means of the like types in the several sets, means for selectively operating said shifting means, controlling means for putting into and out of cooperation said actuating and shifting means of said several sets, said controlling means for each set comprising a lever, a spring forcing this lever towards 75 one of its end positions, means for locking said lever in its opposite position and selectively operating means for moving the said levers of a number of said sets and for engaging them with said locking means.

Signed at Milan, Italy, this 2nd day of 100 May 1923.

RAFFAELLO LA PEGNA.
